(57) **CLAIM**

The ornamental design for an automobile tonneau cover, as shown and described herein.

DESCRIPTION

FIG. 1 is a first side view of an automobile tonneau cover according to the present invention, shown on an example automobile;

FIG. 2 is a second side view of the automobile tonneau cover of FIG. 1;

FIG. 3 is a rear corner perspective view of the automobile tonneau cover of FIG. 1;

FIG. 4 is a front corner perspective view of the automobile tonneau cover of FIG. 1;

FIG. 5 is a front view of the automobile tonneau cover of FIG. 1;

FIG. 6 is a rear perspective view of the automobile tonneau cover of FIG. 1;

FIG. 7 is another rear perspective view of the automobile tonneau cover of FIG. 1; and,

FIG. 8 is a rear view of the automobile tonneau cover of FIG. 1.

The broken line showing of environment is for illustrative purposes only and forms no part of the claimed design.
